UNITED STATES PATENT OFFICE.

FRANK R. STEARNS, OF GREELEY, COLORADO.

GRIPPER FOR PRINTING-PRESSES.

No. 822,027.

Specification of Letters Patent.

Patented May 29, 1906.

Application filed July 25, 1905. Serial No. 271,208.

To all whom it may concern:

Be it known that I, FRANK R. STEARNS, a citizen of the United States, residing at Greeley, in the county of Weld and State of Colorado, have invented a new and useful Gripper for Printing-Presses, of which the following is a specification.

The present invention relates to means for securing paper in a printing-press while the impression is being made.

The principal object is to provide novel means of a simple nature whereby the grippers may be readily adjusted in order to properly coöperate with sheets of different sizes, said adjusting means being efficiently locked in order to maintain the grippers in their adjusted position.

The preferred embodiment of the invention is illustrated in the accompanying drawings, wherein—

Figure 1 is a view in elevation of the improved structure. Fig. 2 is a cross-sectional view, on an enlarged scale and on the line 2 2 of Fig. 1. Fig. 3 is a cross-sectional view on the line 3 3 of Fig. 1. Fig. 4 is a longitudinal sectional view through the structure on the line 4 4 of Fig. 1.

Similar reference-numerals designate corresponding parts in all the figures of the drawings.

In the embodiment illustrated a pivotal frame-bar 5 is employed, having gudgeons 6 at its ends, whereby it may be pivotally mounted, said frame-bar being provided with longitudinal slots 7 and 8, that open through the same side of the bar, one of the slots 7 being considerably larger than the other and extending through the bar, but terminating short of the ends thereof, the other extending the entire length of the bar, as illustrated in Fig. 1. Secured centrally in the slot 7 is a block 9, constituting journal-bearings for the inner ends of a pair of independently-movable screw or worm shafts 10, that extend longitudinally in the slot 7, their outer ends projecting beyond the ends of the frame-bar and carrying knurled operating-heads 11. The said shafts are longitudinally slidable into and out of their bearings and are normally held against longitudinal movement, and consequently against detachment, by retaining-screws 12, threaded into the block 9 and having reduced inner ends 13, which are located in annular grooves 14, formed in the inner ends of the shafts.

The gripper-fingers are designated 15 and

may be of any desired or well-known shape. They are disposed transversely of the frame-bar and are slidable longitudinally thereof, their rear ends being offset, forming guide 60 projections 16, which slide in the slot 8. Said fingers are furthermore provided with offset enlargements 17, that snugly and slidably fit in the slot 7 on opposite sides of the block 9, being provided with threaded openings 18, 65 through which the shafts 10 pass, said shafts thereby having threaded engagements with the fingers. The shafts are normally held against rotation by yielding spring-detents 70 19, secured to the ends of the frame-bar, projecting outwardly and engaging the roughened annular surfaces of the operating-heads 11.

In order to adjust the fingers, the operator has only to grasp the heads 11 and rotate the same in the desired direction, whereupon the 75 shafts being correspondingly rotated the fingers will be carried either toward or away from each other, so that they may be quickly adjusted to properly coöperate with sheets of different sizes. When the adjustment has 80 been obtained, the shafts are automatically and frictionally locked by the springs 19. If it becomes necessary or desirable to remove the fingers 15, by removing the screws 12 the shafts can be readily released, not only from 85 the block 9, but also from said fingers, whereby the fingers can be readily detached and re-applied.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus described my invention, what I claim as new, and desire to secure by Letters Patent, is—

1. In a gripping device of the character described, a pivotal frame-bar having a longitudinal slot and a block located in an intermediate portion of the slot, independent screw 105 or worm shafts having their inner ends journaled in the block and their outer ends journaled in the ends of the frame-bar, said shafts extending longitudinally in the slot, gripper-fingers disposed transversely of the frame-bar and having enlargements located in the slot, said enlargements being in threaded en-

gagement with the shafts, retaining devices for the shafts mounted in the block and engaging the inner ends of said shafts journaled in said block, and holding devices mounted on the ends of the frame-bar and engaging the outer end portions of the shafts.

2. In a gripping device of the character described, a pivotal frame-bar having spaced longitudinal slots opening through the same side of the bar, a journal-bearing located in one of the slots, independent screw or worm shafts having their inner ends journaled in the bearing and their outer ends journaled in the ends of the frame-bar, said shafts extending longitudinally in the slot having the bearing and being provided at their outer ends with knurled heads, spring-clips secured to

the frame-bar and yieldingly engaging the knurled heads to normally hold the same and thereby the shafts against rotation, gripper-fingers disposed transversely of the frame-bar and having terminals slidably engaged in one of the slots, said fingers being furthermore provided with enlargements located in the slot having the shafts and being in threaded engagement with said shafts.

In testimony that I claim the foregoing as my own I have hereto affixed my signature in the presence of two witnesses.

FRANK R. STEARNS.
